US0D1108687S

(12) **United States Design Patent** (10) **Patent No.:** **US D1,108,687 S**
(45) **Date of Patent:** **** Jan. 6, 2026**

(54) **INTEGRATED LIGHTING MODULE**

(71) Applicant: **AMP Plus, Inc.**, Vernon, CA (US)

(72) Inventor: **Brandon Cohen**, Vernon, CA (US)

(73) Assignee: **AMP Plus, Inc.**, Vernon, CA (US)

(**) Term: **15 Years**

(21) Appl. No.: **29/981,337**

(22) Filed: **Dec. 30, 2024**

Related U.S. Application Data

(63) Continuation-in-part of application No. 29/962,228, filed on Sep. 10, 2024, and a continuation-in-part of application No. 29/894,010, filed on Jun. 5, 2023.

(51) **LOC (15) Cl.** **26-05**

(52) **U.S. Cl.** **USPC** **D26/74**

(58) **Field of Classification Search**

(57) **CLAIM**

The ornamental design for an integrated lighting module, as shown and described.

DESCRIPTION

FIG. 1 is a bottom perspective view of an integrated lighting module;

FIG. 2 is a (first) top perspective view thereof;

FIG. 3 is a bottom view thereof;

FIG. 4 is a left-side view thereof;

FIG. 5 is a right-side view thereof;

FIG. 6 is a rear (back) view thereof;

FIG. 7 is a front view thereof;

FIG. 8 is a bottom view thereof; and,

FIG. 9 is another (second) top perspective view thereof. The broken lines in the figures depict portions of the integrated lighting module that form no part of the claimed design.

1 Claim, 9 Drawing Sheets
